CLAIM

The ornamental design for a belt with pouch, as shown and described.

DESCRIPTION

FIG. 1 is a perspective view of a belt with pouch showing our new design;

FIG. 2 is a front elevation view thereof;

FIG. 3 is a back elevation view thereof;

FIG. 4 is a first side elevation view thereof;

FIG. 5 is a second side elevation view thereof;

FIG. 6 is a top view thereof;

FIG. 7 is a bottom view thereof;

FIG. 8 is a cross-sectional view thereof taken substantially along line 8-8 of FIG. 6; and,

(Continued)

FIG. 9 is a perspective view of the belt with pouch in use. The belt with pouch is shown with three symbolic breaks in its length. The appearance of any portion of the article between the break lines forms no part of the claimed design. The portions of the belt with pouch depicted in broken lines forms no part of the claimed design. The broken lines shown in FIG. 9 depict environmental subject matter and form no part of the claimed design.

1 Claim, 7 Drawing Sheets
